LASTING MACHINE

Corwin W. Baker, Stoneham, Mass., assignor to
 United Shoe Machinery Corporation, Flemington, N. J., a corporation of New Jersey

Application May 16, 1945, Serial No. 593,981

8 Claims. (Cl. 12—1)

1

This invention relates to machines for lasting shoes and particularly to improvements in lasting machines of the types shown and described in United States Letters Patent No. 2,397,369, granted March 26, 1946, on an application filed in the name of Edward Quinn and Napoleon A. Monfils. It should be understood, however, that features of the present invention are not necessarily limited in their utility to use in machines of the aforementioned type.

In the machine of the mentioned patent, the shoe is fed along continuously and the stock to be lasted is progressively tensioned in a direction substantially normal to the shoe bottom, movement of the shoe in this direction being prevented by a bottom rest, and then drawn inwardly from the edge of the shoe and toward lasted position, by means of the frictional drag imposed thereon by the action of a driven roll against the operating surface of which the lasting margin of the stock is yieldingly held by means of a pressure member that partially surrounds the roll. As the lasting margin emerges from between the roll and pressure member, it is immediately wiped inwardly from the edge of the shoe and pressed firmly into lasted position against the bottom of the shoe by means of a wiper having a continuous inwiping action. The lasting margin of the stock as well as the margin of the shoe bottom having been previously rendered adhesive, this wiping and pressing action effectively secures the lasting margin of the stock to the shoe bottom in lasted position.

An object of this invention is to provide a novel and improved means for yieldingly holding the lasting margin of the stock against the roll and with this object in view the herein disclosed pressure member is formed with angularly disposed, substantially flat, operating faces which are so arranged as to press the lasting margin of the stock against the roll at two circumferentially spaced locations, one of which is substantially in line with the edge of a shoe being operated upon, while the other is positioned inwardly from the edge of the shoe. Preferably, and as herein illustrated, these two operating faces are formed as separate elements which are so constructed and arranged as to be independently movable away from the roll against the action of yielding means thus to permit the passage between the roll and pressure member of portions of stock that vary in thickness without the loss of pressure thereon at either of said circumferentially spaced locations.

It is also an object of this invention to pro-

2

vide means for facilitating the swinging of a shoe being operated upon in a plane normal to the bottom of the shoe so as properly to present the shoe to the lasting and wiping means. To this end, means are provided for periodically moving the pressure member in a direction away from the roll thus to free the stock from pressure, at least at that location on the roll which is adjacent to the edge of the shoe. With the stock thus momentarily freed at this location, the position of the shoe may be changed, in the direction mentioned, without danger of forming wrinkles on the side of the shoe. However, with the pressure member provided with a separate hinged portion for holding the stock against the roll at a location inwardly from the edge of the shoe, this movement of the pressure member need not be, and preferably is not, sufficient to free the stock at this location, since the stock at this point can accommodate the swinging movement of the shoe. Preferably, and as shown, the aforementioned movement of the pressure member is effected by rapidly vibrating the pressure member in the direction mentioned.

25 These and other objects of the invention will be apparent from the following detailed description of the embodiment shown in the drawings and will be pointed out in the claims.

In the drawings,

30 Fig. 1 is a view in side elevation of a machine embodying this invention;

Fig. 2 is a view in front elevation of the machine shown in Fig. 1, on an enlarged scale and with certain parts in section;

35 Fig. 3 is a plan view of the operating elements of the machine;

Fig. 4 is a detail view of a portion of the machine;

Fig. 5 is a sectional view taken on the line V—V of Fig. 4 and looking in the direction of the arrows; and

40 Figs. 6 and 7 are schematic views of the operating elements of the machine showing these elements in two different positions.

45 Referring to the drawings, the illustrated machine is provided with a driven tensioning and feeding roll 10, having an operating face 11 for engaging the lasting margin of the stock; a pressure member, or sleeve, comprising a body portion 12 and a hinged part 14, for holding the stock against the operating face of the roll at two locations spaced circumferentially thereof; an endless flexible wiping element, comprising a chain 16; and an edge gage roll 18 and a bottom rest 20.

50 The roll 10 is secured to the lower end of a shaft

30 which is journaled in a bearing block 32. This bearing block has a T-shaped arcuate rib 34 which is slidably mounted in a correspondingly shaped arcuate groove 35 formed in a supporting bracket 36, Figs. 2 and 3. The bracket 36 is likewise provided with a T-shaped arcuate rib 38 that is slidably mounted in a correspondingly shaped arcuate groove 40 in a plate 42. These arcuate ribs and grooves are arranged to permit the varying of the inclination of the shaft 30, together with the roll 10, with respect to a horizontal plane passing through the bottom of the roll, and clamping bolts 43 and 45 are provided for locking the bearing block 32 and supporting bracket 36, respectively, in adjusted position. The arc of the rib 38 and groove 40 is swung about a center on a vertical line tangent to the right-hand side of the roll 10, as viewed in Fig. 3, while the arc of the rib 34 and groove 35 is swung from a center on a horizontal line tangent to the right-hand side of the bottom face of the roll, as viewed in Fig. 2. Thus, when the inclination of the roll is varied as above explained, the vertical position of the aforementioned part of the roll will not be altered.

The plate 42 is secured to a slide 44 by means of a tongue 46 and groove 48 and clamping bolts 50 which pass through elongated slots 51 in the plate. When these bolts are loosened the roll may be adjusted toward or away from the wiping chain 16.

The slide 44 is supported in a guide bracket 52 which is secured to a frame member 54 that is mounted on the top of a column 56 of suitable height, Fig. 1. A cam roll 58, carried by the slide 44, engages a cam groove 60 formed in a cam bar 62 which is mounted for vertical sliding movement in the bracket between rolls 64, 64. Vertical movement of the cam bar will move the bearing block 36 and roll 10 forwardly or rearwardly of the machine for purposes which will presently appear.

The shaft 30, and roll 10, are driven from a main drive shaft 68 which is journaled in the upper end of the frame 54 and provided with a belt pulley 70. The shaft 68 extends forwardly and into a gear housing 72, secured to the frame 54 by bolts 74, where it drives an idler gear 76 through helical gear 78, Fig. 2. Formed integrally with this idler gear 76 is a gear, not shown, which meshes with a gear 82, secured by setscrew 84 to a vertical shaft 86 that is journaled in the housing 72 in anti-friction bearings 88 and 90. The gear 82 drives, through a reduction train comprising gears 92, 94 and 96, a shaft 98, likewise journaled in the housing and projecting through its lower wall. This shaft is connected to the shaft 30 by means of an extensible shaft assembly indicated by the reference character 100 and including universal joints 102 and 104. A sheet metal guard housing 106 surrounds the extensible shaft 100, as shown in Figs. 1 and 2.

The body portion 12 of the pressure member, or sleeve, is secured, by means of a tongue and groove and a clamping bolt 110, to the lower end of an arm 112 which is pivotally mounted on the bearing block 32 by means of a pin 114 that extends through spaced flanges 116, see Fig. 4. The bolt 110 extends through an elongated slot 118 in the body portion 12, which, when the bolt is loosened, permits adjustment of the pressure member, or sleeve, laterally of the machine and relatively to the roll 10. The hinged part 14 is pivotally mounted on the body portion 12 by means of a pin 120 and is yieldingly urged in a

counterclockwise direction about the pin 120, Figs. 6 and 7, by a compression spring 122 which is fitted in recesses 124, 126 in the body portion and hinged part, respectively. A rod 130 having a spherical end 132 is connected to the arm 112 by means of a plate 134 and screw 136. This rod extends rearwardly of the machine from the arm 112 and passes through an aperture 138 in a bracket member 140 that is secured to the frame 54 by means of bolts 142, 142, Figs. 1, 3 and 6. Interposed between a collar 144, adjustably secured to the rod 130 by means of a setscrew 146, and the bracket 140 is a compression spring 148.

The cam bar 62 is connected, by means of a rod 150, to a treadle 152 which is normally elevated by means of a spring 154. Depression of this treadle will move the cam bar downwardly to the position shown in Fig. 1 in which position of the cam bar the slide 44 and roll 10 will be moved rearwardly of the machine. As the roll goes back, the arm 112 is swung about the pivot pin 114 by the action of the rod 130 and compression spring 148 until the pressure member, or sleeve, nearly engages the roll, after which the continued movement of the roll will compress the spring 148. In order to prevent actual contact of the roll on the sleeve, a stop screw 155 is provided, see Figs. 3 and 4, this screw being so set as to engage the bearing block 32 and hold the sleeve spaced from the roll a few thousandths of an inch. Fig. 3 shows the roll and sleeve in the positions assumed when the treadle is thus depressed and with the spring 148 under compression; while Fig. 7 shows these parts in the same position and with the lasting margin M of the cover of a platform shoe S pressed against the roll by the pressure member. Upon release of the treadle it will be moved upwardly by the spring 154 and a reverse action will take place; the pressure member, or sleeve, following the forward movement of the roll, which now occurs, until engagement of a collar 156, on the rod 130, with the bracket 140, arrests forward movement of the pressure member. Thereafter, the roll moves away from the pressure member until the parts assume the positions shown in Fig. 6. The spring 122 is weaker and less effective than the spring 148 and the pressure member is so adjusted relatively to the roll that the hinged part 14 will contact the lasting margin M just before the fixed part 12 does. Thus the spring 122 will be slightly compressed, when the parts are in the position shown in Fig. 7 and the hinged part 14 will be moved away from an abutment surface 157 on the body portion 12, Fig. 7.

The shaft 30 carries, just below the bearing block 32, a four-pointed cam 160 which is in alignment with a cam roll 162 mounted on the lower end of an arm 164 which is pivoted on the arm 112 by means of a pin 166 which extends between two ears 168, 168 on the arm, see Figs. 3 and 4. Above the pin 166, a compression spring 170 is interposed between the upper end of the arm 164, which spring holds the arm against a stop screw 172. By suitable adjustment of the stop screw 172, the roll 162 may be moved into engagement with the cam 160 and, when this is done, the arm 112 will be moved rearwardly by each high point of the cam and the body portion 12 of the pressure member, or sleeve, will be moved away from the roll four times during each revolution of the roll. When 70 the body portion of the pressure member, or

sleeve, is thus periodically moved away from the roll, the hinged part will still maintain its pressure against the lasting margin M since the separating movement, effected by the cam 160 , is not sufficient to close the gap between the hinged part 14 and the abutment surface 157 on the body portion 12 , but only enough to relieve the pressure of surface 12 on the lasting margin M .

The wiping chain 16 is carried in a housing 180 which is mounted for angular adjustment about a boss 182 on the lower face of the housing 72 , this boss being centered about the axis of the shaft 86 , and two clamping bolts 184 , 184 are provided for holding the housing and chain in adjusted position. The chain runs over two idler sprockets 186 , 188 , a take-up sprocket 190 , and a driving sprocket 192 , see Fig. 2. The driving sprocket 192 is mounted on a shaft 194 , journaled in the housing 180 , and carrying a bevel gear 196 which meshes with another bevel gear 197 on the shaft 86 . The take-up sprocket 190 is mounted on an arm 198 which is adjustably secured to the housing 180 by means of a clamping bolt 200 . The two idler sprockets 186 and 188 are journaled on the lower end of a slide 202 which is mounted for adjustment vertically of the housing 180 by means of a clamping bolt 204 that passes through an elongated slot 206 in the housing 180 .

The edge gage roll 18 is journaled on a stud 210 carried by a block 212 which is mounted for adjustment forwardly and rearwardly of the machine by means of a clamping bolt 216 which passes through a slot 214 in an arm 218 , Figs. 6 and 7. This arm is likewise mounted for adjustment, laterally of the machine, by means of a clamping bolt 222 and slot 220 on a bar 224 , and this bar is mounted for adjustment vertically of the machine, by means of a bolt 232 and slot 234 , on a slide 236 . The slide 236 is mounted for reciprocating movement in a guide bracket 226 on the frame member 54 and carries a cam roll 228 which engages a cam groove 230 in the cam bar 52 .

The bottom rest 20 is mounted on the bearing block 32 for angular adjustment about the axis of the roll 10 by means of an arcuate boss 240 on the bearing block, and a bolt 242 which passes through a slot 244 in the upper end of the bottom rest.

The machine above described operates, in general, in the same manner as the machine of the above-mentioned patent, that is to say, when the treadle is depressed and the operating elements are in the position shown in Fig. 7, the operating surface 11 of the inclined roll 10 exerts a frictional drag on the lasting margin of the stock, e. g., the lasting margin M of the cover of a platform shoe S , shown in broken lines in Fig. 2, having a platform P and an upper U mounted on a last L . It will be understood, of course, like the machine of the above-mentioned patent, that the herein illustrated machine may be used for operating on the lasting margin of the upper of a conventional shoe. This frictional drag, which is enhanced by providing the surface 11 with a plurality of projections, illustrated, diagrammatically, in the drawings by crossed lines, see Fig. 4, has a vertical component which tends to tension the lasting margin in a direction substantially perpendicular to the bottom of the shoe and a horizontal component which tends to feed the shoe. Also, due to the fact that the lasting margin is wrapped, partially, around the roll by the pressure member or sleeve, this frictional drag

has a component that tends to draw the lasting margin inwardly from the edge of the shoe and over the shoe bottom. The operator merely supports the shoe and holds it against the edge gage roll 18 as it is fed along by the roll, tipping the shoe in a vertical plane to accommodate the curvature of the shoe bottom and so as to hold the shoe bottom always in engagement with the wiper chain 16 and the shoe bottom rest 20 . The operator also swings the shoe in a horizontal plane so as to keep a line tangent to the edge of the shoe at the point of operation of the roll substantially normal to a vertical plane extending from the front to the back of the machine.

As this tensioning, overdrawing and feeding action progresses along the marginal edge of the shoe, the tensioned and overdrawn lasting margin is immediately wiped down onto the shoe bottom by the chain wiper 16 which, as can be seen in Fig. 7, has a component of movement inwardly from the edge of the shoe and lengthwise of the shoe in the direction of feed, see the arrow in Fig. 7. The relative values of these components of the wiping action may be readily varied to accommodate different working conditions by loosening the bolts 184 , 184 and rotating the housing 180 about the boss 182 , the center of which is substantially in line with the edge of the shoe so that such rotary adjustment will not alter the position of the chain with respect to the roll and sleeve.

The lasting margin of the stock is held against the roll by the pressure member, or sleeve, at two points spaced circumferentially of the roll, i. e., at the point of tangency of the flat surface of the body portion 12 and at the point of tangency of the hinged part 14 . The intensity of pressure exerted on the lasting margin by the body portion 12 of the sleeve is determined by the spring 148 and may be varied by changing the position of the collar 146 . The pressure at the second point of contact is substantially constant and is determined by the strength of the spring 122 which is, as already noted, somewhat weaker than the spring 148 . In adjusting the sleeve or pressure member on its supporting arm 112 , it is so positioned, laterally of the machine, that the body portion 12 and hinged part 14 would each contact the roll at about the same time should the treadle be depressed with no work in the machine. However, with the lasting margin M interposed between the roll and sleeve when the treadle is depressed the hinged part will strike the lasting margin first, due to the swinging movement of the arm 112 about the pin 114 , and when the treadle has been fully depressed the hinged part will have been swung about its pivot pin 120 so as to compress the spring 122 .

By forming the sleeve in two angularly disposed parts, as shown, the friction between the outside surface of the moving lasting margin M and the stationary sleeve parts 12 and 14 is substantially reduced and the action of the machine considerably improved. The illustrated construction of the pressure member, or sleeve, also facilitates the operation of the machine on lasting margins which are non-continuous or lapped in the manner shown in Fig. 7. As will be apparent when the lapped portion enters between the roll and body portion 12 of the sleeve, the spring 148 will be somewhat compressed and the body portion will move away from the roll enough to accommodate the greater thickness of the lasting margin at this point. However, the spring 122 will now move the hinged part

toward the roll so that the single thickness portion of the lasting margin will be pressed against the roll with substantially the same pressure as before. Conversely, when the lapped portion of the margin reaches the second point of contact on the roll and with the single thickness portion between the first point of contact, i. e., between the body portion 12 and the roll, the spring 148 will move the body portion toward the roll thus to maintain the pressure at this point while, at the same time, the spring 122 will yield enough to allow the hinged part to move away from the roll and accommodate the greater thickness of the lasting margin at that point. Thus the lapped portion may pass between the roll and sleeve without loss of pressure of the lasting margin against the roll at either point.

As explained above, the operator holds the bottom of the shoe always in engagement with the chain wiper 16 and with the bottom rest 20. In order to do this the operator must swing the shoe in a vertical plane to accommodate the curvature of the shoe bottom. Where there are abrupt changes in the contour of the shoe bottom, as for example along the shank portion, see Fig. 2, such swinging movement of the shoe may be quite pronounced and so great that the portion of the lasting margin which is engaged by the body portion of the sleeve and roll cannot readily adjust itself in a vertical plane by slipping between the roll and sleeve, but instead will remain fixed, while the shoe is swung, and cause some wrinkling on the side of the platform P. To avoid this, the cam 160 may be rendered operative to vibrate the body portion 12 and move it periodically away from the roll. Each time that the body portion is thus moved away from the roll the lasting margin will be momentarily freed at this point and may readily adjust itself in a vertical plane to accommodate the swinging movement of the shoe in this direction. Since there are several points on the cam 160 this action will occur a number of times for each revolution of the roll and an ample opportunity for the lasting margin to adjust itself to even the most rapid swinging movement of the shoe is presented. During this vibrating of the body portion of the sleeve, pressure of the hinged part is not entirely relieved. However, the lasting margin at this point is substantially parallel to the plane of the shoe bottom and can readily flex or bend without causing wrinkles at the side of the shoe. Under normal conditions and with the type of shoe usually encountered, the character of the shoe bottom is such that the lasting margin will accommodate itself by slipping between the roll and sleeve without the necessity for vibrating the sleeve because of the frictional action inherent in the machine. However, for extreme conditions of shoe bottom curvature the use of the vibrating cam may be desired and this can be easily obtained by a simple adjustment of the screw 172.

The edge gage roll 18 is adjusted vertically so as to contact the edge of the shoe just below the plane of the bottom face of the platform, see Fig. 2, and in a horizontal direction, toward the front of the machine, so that it extends just a small distance beyond the point of contact of the body portion 12 of the sleeve with the lasting margin M, Fig. 7. Thus the tensioning action of the roll on the lasting margin will be upwardly and outwardly away from the edge of the platform as is desirable. The edge gage roll is also positioned horizontally and in a direction extending lengthwise of the shoe in the direction of

5 feed somewhat beyond the point of contact of the body portion of the sleeve with the lasting margin so as not to interfere with the tensioning action of the roll which occurs at this point. In this position the edge gage roll also holds the lasting margin against the edge of the platform and thus tends to prevent any loosening thereof before the lasting margin is wiped down onto the shoe bottom by the chain wiper 16.

Having described the invention, what I claim as new and desire to secure by Letters Patent of the United States is:

1. A lasting machine having a driven roll for applying a frictional drag on the lasting margin of stock to be lasted, and a member for pressing said lasting margin against the roll, said member being formed with two angularly disposed operating faces for engaging the stock at locations spaced circumferentially of the roll.

2. A lasting machine having a driven roll for applying a frictional drag on the lasting margin of stock to be lasted, and a member for pressing said lasting margin against the roll, said member being formed with two angularly disposed operating faces so arranged that one will engage the stock at a location on the roll adjacent to the edge of a shoe presented to the machine and the other at a location inwardly from the edge of the shoe bottom.

3. A lasting machine having a driven roll for applying a frictional drag on the lasting margin of stock to be lasted, and a member for pressing said lasting margin against the roll, said member comprising a body portion formed with a surface for engaging the stock at a location on the roll adjacent to the edge of a shoe presented to the machine and a part having a surface for engaging the stock at a location inwardly from the edge of the shoe, said part being yieldingly movable, relative to said body portion, away from the roll.

4. A lasting machine having a driven roll for applying a frictional drag on the lasting margin of stock to be lasted, and a member for yieldingly pressing said lasting margin against the roll, said member comprising a body portion formed with a surface for engaging the stock at a location on the roll adjacent to the edge of a shoe presented to the machine and a part hinged to the body portion, said hinged part having a surface for engaging the stock at a location inwardly from the edge of the shoe and a spring for swinging the hinged part toward the roll.

5. A lasting machine having a driven roll for applying a frictional drag on the lasting margin of stock to be lasted, a cooperating member for pressing said lasting margin against the roll, means for yieldingly urging said member toward the roll, and means for periodically moving said member away from the roll.

6. A lasting machine having a driven roll for applying a frictional drag on the lasting margin of stock to be lasted, a member for pressing the lasting margin against the roll, said member being formed with two angularly disposed operating faces for engaging the stock at locations spaced circumferentially of the roll, means for yieldingly urging said member toward the roll, and means for periodically moving said member away from the roll.

7. A lasting machine having a driven roll for applying a frictional drag on the lasted margin of stock to be lasted, a member for pressing said lasting margin against the roll, said member comprising a body portion formed with a surface for engaging the stock at a location on the roll adja-

75

cent to the edge of a shoe presented to the machine and a part having a surface for engaging the stock at a location inwardly from the edge of the shoe, said last-named part being yieldably movable relative to said body portion, away from the roll, means for yieldingly urging said member toward the roll, and means for periodically moving said member away from the roll.

8. A lasting machine having a driven roll for applying a frictional drag on the lasting margin of stock to be lasted, a member for pressing the lasting margin against the roll, said member comprising a body portion formed with a surface for engaging the stock at a location on the roll adjacent to the edge of a shoe presented to the machine and a part hinged to the body portion, said hinged part having a surface for engaging the stock at a location inwardly from the edge

of the shoe and a spring for swinging the hinged part toward the roll, means for yieldingly urging said member toward the roll, and means for periodically moving said member away from the roll.
